(57) **CLAIM**

The ornamental design for a display panel or screen with animated graphical user interface, as shown and described.

DESCRIPTION

FIG. 1 is a first front view of a display panel or screen with animated graphical user interface showing our new design; FIG. 2 is a second front view thereof; FIG. 3 is a third front view thereof; FIG. 4 is fourth front view thereof; FIG. 5 is a fifth front view thereof; FIG. 6 is a sixth front view thereof; FIG. 7 is a seventh front view thereof; FIG. 8 is an eighth front view thereof; and, FIG. 9 is a ninth front view thereof.

The image of FIGS. 1-9 transitions sequentially.

The even-dash broken lines of the graphical user interface and the even-dash broken lines representing the display panel or screen and form no part of the claimed design. The appearance of the transitional image sequentially transitions between the images shown in FIGS. 1-9. The process or period in which an image transitions to another forms no part of the claimed design.
